DESIGN FOR A BRAIDED SHOE

Saul Horwitz, New York, N. Y.

Application January 26, 1935, Serial No. 55,076

Term of patent 3½ years

To all whom it may concern:

Be it known that I, Saul Horwitz, a citizen of the United States, residing in the Borough of Manhattan, in the city, county, and State of New York, have invented a new, original, and ornamental Design for a Braided Shoe, of which the following is a specification, reference being had to the accompanying drawing, forming part thereof.

Fig. 1 is a side perspective view of a shoe embodying my new design.

Fig. 2 is a top plan perspective view of the same. The characteristic feature of my new design is the integrally braided appearance presented by the shoe upper and quarter with strips radiating from a common area.

I claim:

The ornamental design for a braided shoe as shown and described.

SAUL HORWITZ.
